UNITED STATES PATENT OFFICE.

NEALON D. RUTHERFORD, OF LANSING, MICHIGAN, ASSIGNOR TO UNITED ENGINE COMPANY, A CORPORATION OF MICHIGAN.

MILKING-MACHINE.

1,391,980.

Specification of Letters Patent. Patented Sept. 27, 1921.

Application filed September 25, 1920. Serial No. 412,748.

To all whom it may concern:

Be it known that I, NEALON D. RUTHERFORD, a citizen of the United States, residing at Lansing, in the county of Ingham and 5 State of Michigan, have invented certain new and useful Improvements in Milking-Machines, of which the following is a specification.

The invention relates to mechanical milkers of the intermittent suction operated type and the primary object of the invention is to provide improved valve chamber mechanism for controlling the intermittent suction impulses to be transmitted to teat cup apparatus on machines of the described character.

Other objects of the invention will appear from the following description directed to the preferred embodiment thereof, as shown 20 in the drawings, the novel features being defined in the appended claims.

In the said drawings, Figure 1 is a view in vertical section of the preferred form of my improved chamber.

Figs. 2 and 3 are elevation and top plan views respectively of the valve chamber, and Fig. 4 is a view similar to Fig. 2 being taken at right angles thereto.

Fig. 5 is a view similar to Fig. 1 of a modified form of the valve and chamber, and Figs. 6 to 8 inclusive are views similar to Figs. 2 to 4 inclusive showing modified forms of the valve and valve chamber of Fig. 1.

Referring to the preferred form of the invention shown in Figs. 1 to 4 inclusive, the wall of the chamber of cylindrical form with a dome-shaped or hemispherical top is indicated generally by reference character 40 and is provided adjacent the top of the cylindrical body thereof with a peripheral flange 11 perforated at suitable intervals and threaded to receive screws 12 for securing the chamber to the top cover or lid 13 of a 45 milk receptacle. Leading from the curvilinear or dome-shaped top portion are two nipples 14, 15, the former having flexible pipe connection 16 leading to a suitable teat cup device commonly called a claw, and the latter also having a flexible connection 17 leading to a suction pump device of any suitable form as commonly used in this type of milking machine. The main body portion of the chamber 10 is cylindrical in form and is 55 open at the bottom, being provided near the

bottom extremity with a peripheral thickened portion or bead 18 adapted to furnish a seat 19 for the bottom closure valve member, indicated generally by the reference character 20. The latter is provided with 60 a peripheral seat portion 20^a adapted to co-operate with the seat 19 of the valve chamber to form an air tight closure whenever the air on the interior of the chamber is exhausted, and there are upstanding spaced 65 members 20^b and 20^c preferably formed integral with valve 20 and having in their outer faces indentations or sockets 20^d adapted to receive suitable means for anchoring or holding the valve 20 adjacent the lower 70 end of the chamber and at the same time allowing sufficient movement for the valve to open and close in relation to its seat 19 on the chamber. This means consists of two pins one of which, as indicated by reference 75 character 21, is fixed by being a drive fit in a perforation through the thickened portion 18 at the bottom of the chamber and has a part thereof projecting to the interior of the chamber for co-operating with one of the 80 cavities 20^d of the valve. Diametrically opposite the fixed pin 21 I provide a removable or adjustable pin for engaging the cavity 20^d in the diametrically opposite projection 20^b of the valve. This pin is designated 85 by reference character 22 and is screw threaded for a portion of its length, as indicated, and provided at its outer extremity preferably with a knurled head 23. In order to provide a suitable bearing portion 90 for the threaded part thereof, I provide an enlarged opening in the thickened wall 18 of the chamber, which is screw threaded and takes the co-operating threaded plug 24, having a suitable head, as indicated, so that it 95 may be locked in its adjusted position against the chamber wall and furnishes a suitable bearing against which the knurled head 23 of pin 22 may be locked in its adjusted position, the central portion of the 100 plug 24 being perforated and threaded to receive the threaded portion of pin 22, as indicated.

The above described construction of the valve end of the chamber 10 affords a convenient means of detachably securing the suction closed valve 20 to the lower end of the chamber, for it will be apparent that there is sufficient play or looseness between the projections 20^b and 20^c and the walls of 110

the chamber so that when the pin 23 is screwed outwardly so as to withdraw the end thereof projecting into the chamber and the valve 20 will easily drop down at that side 5 and may be pulled off the pin 21 so as to be detached from the chamber for cleaning purposes, but when the pin 22 is in position and within the cavity 20^a of the valve it will also be apparent that the valve will be held 10 in its working position capable of being seated to form an air tight closure at the bottom of the chamber when there is a vacuum produced within the chamber, and when the vacuum is relieved on the return stroke of 15 the pump it will be apparent that the valve will drop by gravity to the open position as illustrated in Fig. 1.

The manner of operation of a suction valve in a milking machine of the described character is well understood, it being noted that 20 when the suction pump exhausts the air from the chamber through nipple 15 and flexible tube 17 leading to the pump the inrush of air current from below will lift the valve 20, which is preferably made of aluminum so as to be as light as possible, to its closed position and the vacuum thus produced will be maintained within the chamber 25 and extend through the nipple 14 and flexible tube 16 so that there will be a pull exerted upon the teat cup device connected with tube 16.

In the modified form of the invention of Figs. 5 to 8 inclusive the chamber of substantially the form shown in Fig. 1 is indicated by reference character 30 and it is provided with the nipples and flexible tubes 14 to 17 inclusive like the valve chamber of Fig. 1. The cylindrical chamber 30 is in 40 this instance provided with a peripheral enlargement near the spherical top portion, as indicated by reference character 31, the same being slightly grooved to have the cover 32 of a milk receptacle attached thereto by soldering, as indicated at 33. As in the case of the chamber of Fig. 1 the bottom of the chamber 30 is provided with a thickened portion 34, which is perforated at diametrical locations and provided with fixed pins 50 35 which protrude a short distance, as illustrated, on the interior of the chamber, the bottom portion of which is provided with the valve seat 36. A valve 37 having a circular seat portion, as indicated at 37^a, is 55 provided, the form of same being illustrated in Figs. 6 to 8 inclusive. This valve, like the valve of Fig. 1, is preferably also formed of aluminum or some analogous light material, and is provided with an upwardly extending portion 37^b, which has diametrically opposed ledges 37^c, each of which are provided with an undersurface arranged at a slight angle to the normal plane of the valve 37. The angular under-surfaces are indicated generally by reference character 37^d

and each is provided with an indentation 37^e of semicircular form in cross section being adapted to coöperate with the pins 35 and forming a sort of bayonet joint so that when the ledges 37^c are arranged angularly 70 in the general form of screw threads the valve 37 may be inserted into its seating position in the lower end of the chamber and by a turn cause the thin portion of the ledge to pass over the pins 35, and said pins may 75 be caused to engage the valve in the indentations 37^e and the valve prevented from rotating further by the thickened portion of the ledge. This construction is efficient and 80 obviously is much easier of insertion and attachment to the lower end of the valve chamber than is the valve of the form of Fig. 1, which requires manipulation of the screw to secure the valve in its working position.

In order that the invention might be 85 understood the details of the preferred embodiment of the invention have been described but it is not desired to be limited to the exact details, since it will be apparent that persons skilled in the art may resort to 90 various modifications without departing from the purpose and spirit of the invention.

I claim:

1. In a valve mechanism for milking machines, the combination of a chamber provided with outlets leading to a vacuum producing device and to a teat cup, said chamber being provided with a downwardly opening lower extremity, a valve seat adjacent said lower extremity, a valve for coöperating with said seat at the lower extremity of the chamber and comprising a substantially circumferential member having a peripheral seat face thereon adapted to coöperate with the valve seat on the chamber, a vertically extending member above said valve face, said vertically extending member on said valve being undercut, and means secured to the wall of the chamber on the interior thereof adapted to extend into the undercut portion of the extension on the valve to secure the latter in its normal working position.

2. In a valve mechanism for milking machines, the combination of a chamber provided with outlets leading to a vacuum producing device and to a teat cup respectively, said chamber being provided with a downwardly opening lower extremity, a valve seat adjacent said lower extremity, a valve for coöperating with said seat at the lower extremity of the chamber and comprising a substantially circumferential member having a peripheral seat face thereon, a vertically extending member on the valve face formed integrally therewith, said vertically extending member having diametrically opposed branches undercut in a direction angularly to the plane of the valve seat, there being indentations in the undercut surfaces on the 130

- said valve chamber, and means secured to the wall of the chamber on the interior thereof adapted to extend into the diametrically undercut portions of the extension on the valve to secure the latter in its normal working position in relation to the valve seat, and being adapted to prevent the valve while working from becoming detached from the valve chamber.
- 10 3. In a valve mechanism for milking machines, the combination of a chamber provided with outlets leading to a vacuum producing device and to a teat cup respectively, said chamber being provided with a downwardly opening lower extremity, a valve seat adjacent said lower extremity and formed integrally therewith, a valve for coöperating with said seat comprising a substantially circumferential member having a peripheral seat face thereon adapted to coöperate with the valve seat at diametrically opposite portions thereof adapted to extend on the interior of the chamber when the valve is in working position, and means secured to the wall of the chamber on the interior thereof adapted to coöperate with said vertical extensions to secure the valve in its normal working position.
4. In a valve mechanism for milking machines, the combination of a chamber provided with outlets leading to a vacuum producing device and to a teat cup respectively, said chamber being provided with a downwardly opening lower extremity, a valve seat adjacent said lower extremity and formed integrally therewith, a valve for coöperating with said seat comprising a substantially circumferential member having a peripheral seat face thereon adapted to coöperate with the valve seat on the chamber, vertical extensions on the valve at diametrically opposite portions thereof adapted to extend on the interior of the chamber when the valve is in working position, and means secured to the wall of the chamber on the interior thereof adapted to coöperate with
- said vertical extensions to secure the valve in its normal working position comprising a pin fixed in the wall of the chamber and a second pin screw threaded and being adjustably secured in the chamber wall.
5. In a valve mechanism for milking machines, the combination of a valve chamber, a valve seat surrounding an opening in the chamber wall, a valve coöperating with said seat, said valve being provided with vertical extensions on diametrically opposite sides of the valve and said vertical extensions being provided with laterally extending sockets, a pin fixed in the wall of the chamber and extending to the interior thereof for coöperating with one of the sockets on the vertical extension on the valve and a second pin adjustably secured in the wall of the chamber and extending to the interior and being adapted to coöperate with the socket of an extension on the valve to retain the valve in its normal working position.
6. In a valve mechanism for milking machines, the combination with a chamber provided with a valve seat, a valve adapted to coöperate with said seat, said valve being provided with diametrically located vertical extensions each of which have laterally opening sockets therein, a fixed pin on the interior wall of the chamber for coöperating with one of the sockets of the valve, a member screw threaded in the chamber wall and a screw threaded pin adapted to coöperate with said screw threaded member for engaging the socket in the other vertical extension of the valve to retain the valve in its normal working position.

In testimony whereof I have signed my name to this specification, in the presence of two subscribing witnesses, on this 9th day of September A. D. 1920.

N. D. RUTHERFORD.
